1

This invention comprises improvements in or relating to methods of shaping metal workpieces and to metal working machines therefor, and relates to methods of and machines for bending and shaping metal bars, strips, rods, and like work-pieces.

Heretofore it has been considered very difficult, and in some cases almost impossible, to bend a flanged work-piece, for example of U section, composed of mild steel or other hard metal to any appreciable degree of curvature, because the reduction in length of that part of the work-piece lying along the inside of the curve when the work-piece is bent and the consequent compression of the metal in this region causes the work-piece to crinkle and distort. Certain of the simpler curved flanged forms can be hot forged in a die press, but as the forms required become more complex and the degree of curvature greater, higher forging pressures are necessary and the number of rejects due to distortion of the work-piece grows until a stage is reached when it is not a practical proposition to produce the forms by ordinary forging methods. This has hitherto imposed a severe limitation upon the designs of, for example, articles such as bumpers or fenders for motor vehicles.

It is an object of the present invention to provide a method and a machine whereby satisfactory curved flanged forms can be produced from straight or slightly curved flanged work-pieces and also from unflanged work-pieces, by cold bending.

According to the present invention a method of shaping a metal workpiece consists in placing the work-piece against a former, pressing a shoe on to the work-piece toward the former by fluid-pressure-operated means so that the shoe forces the work-piece to conform to the former at one part of its length, said fluid-pressure-operated means being pivotally mounted to swing about a centre located behind the former surface, and thereafter, while maintaining pressure on the shoe toward the former, applying lateral force to the fluid-pressure-operated means to effect a shifting of the place of application of such pressure progressively along the shoe and so rolling the shoe and former one over the other with the workpiece between them to cause the metal of the workpiece to flow into conformity with the shape of the former.

The present invention further includes the provision in a metal-working machine of the combination of a curved former, means to hold a work-piece in place against the former for shaping, a shoe capable of rolling upon the work-

2

piece against the former, fluid-pressure-operated means to press the shoe, work-piece, and former together, said fluid-pressure-operated means being provided with a nose to apply the pressure and being movably mounted so that the nose is capable of moving laterally relative to the shoe, and means to effect said relative movement of the nose and shoe to shift the place of application of the pressure to the work-piece progressively along its surface while maintaining the fluid pressure.

The shoe presses the work-piece against the former over a narrow area only at any one time, and this narrow area of pressure is caused to travel slowly and progressively over the work-piece so that the metal of the work-piece flows and the work-piece is gradually smoothed or ironed to the shape of the former; the movement of the shoe must be slow enough to allow the cold metal time to flow, and the result is that the finished form does not display any distortion or crinkles although the flanges of the work-piece show a very slight thickening towards their edges along the inside of the curve. Since the work-piece is pressed to the former progressively, and over only a narrow area at any given instant, the pressure required is only a fraction of that which would be necessary to perform an equivalent operation in a die-press in which the work-piece is formed over the whole of its length simultaneously at one stroke of the press ram.

Preferably the fluid-pressure-operated means is mounted on a swinging arm having its centre of movement on the opposite side of the former to the work-piece, which arm is connected to a further fluid pressure operated device for causing it to swing.

Also in the preferred form of the invention the lateral shift of the fluid-pressure-operated means for applying pressure to the work-piece is in a substantially horizontal plane and the shoe is supported on a flat table arranged at a level below the former and the fluid-pressure-operated means and parallel to the plane of movement of the fluid-pressure-operated means over which table the shoe is free to slide, and the table may form part of the swinging arm.

According to a feature of the invention the swinging arm also carries auxiliary fluid-pressure-operated means capable of pressing upon the shoe when desired, at a position offset from the place of application of pressure of the main or first said fluid-pressure-operated means to assist in swinging the shoe angularly at positions where the curvature of the former changes rapidly.

One form of machine in accordance with the

invention for forming motor car bumpers will now be described by way of example, and with reference to the accompanying drawings in which:

Figure 1 is a plan of the machine.

Figure 2 is an elevation looking in the direction of the arrow 2, of Figure 1, with part of the machine omitted.

Figure 3 is a part plan of the machine with parts broken away, showing the movable members in different relative positions to those in Figure 1.

Figure 4 is a part plan with parts broken away showing the movable members disposed in a third series of relative positions.

Figure 5 is a plan of superstructure built on the machine table.

Figure 6 is an elevation of the structure shown in Figure 5.

Figure 7 is a plan of the shoe table and swinging arm carrying it.

Figure 8 is an elevation of the arm in section on the line 8—8 of Figure 7.

Figure 9 is a side elevation of part of the swinging arm, and the arm pivot, showing the shoe and associated parts.

Figure 10 is an elevation in section on the line 10—10 of Figure 9, and

Figure 11 is an elevation of the clamping means for the work-piece.

The machine has an underframe 11 secured rigidly to the floor and comprising a plurality of rolled steel sections, and upon the under frame is a heavy rectangular horizontal plate 12 which forms the main bed of the machine. A built-up superstructure 13 is secured upon the bed-plate near one corner thereof, and rolled steel section pillars 14 extend upwardly from the superstructure 13 and support a head-plate 15 near the top of the machine.

A horizontal plate 16 is bolted on the superstructure 13 and projects beyond the superstructure, in a direction generally towards the centre of the bed-plate 12, so that it overhangs the bed plate at a distance of about 8 inches above it, and a second plate 17 overlies the plate 16 and also overhangs the bed-plate in the same direction but not to such a great extent as the plate 16, its overhanging edge 18 being set back towards the superstructure 13 with respect to the overhanging edge 19 of the lower plate 16, so that there is a step 20 formed at the limit of the overhang of the two plates. A horizontal former block 21 is bolted along the overhanging edges of the plates 16, 17 being cut away to fit over the step 20, and the outer edge of the block 21, that is the edge farthest from the plates 16, 17, which extends horizontally above the bed plate, is convexly curved and constitutes a male former 22 with a profile shaped according to the desired internal curvature and shape of the motor car bumper it is desired to produce upon the machine.

As illustrated, the former profile is of a length and curvature such as to produce a so-called "quarter-bumper," a pair of which are fitted to the rear of a car, one towards each side. The former profile is of uniform vertical cross section, and has a very gradual curve along its length near one end 23, that is the right hand end as viewed from the convex or front side of the former, which curve corresponds to that part of the quarter-bumper which lies along the back of the car, and the former curves round fairly sharply near the opposite or left hand end 24, to correspond to a part of the bumper which wraps

around the side of the rear wing of the car. The sharp curve of the bumper finishes with an in-turned end which is slightly cupped.

A vertical pivot pin 25 is situated upon the concave or inner side of the former profile, being journalled through the head-plate 15, the plate 16, 17, and the bed plate 12, and an arm 26 extending across the bed plate 12 upon the convex side of the former swings above the bed plate about the pivot pin 25 and comprises an upper horizontal strap 27 and a lower strap 28 passing respectively above and below the plates 16, 17 and the former block 21 and united at their outer ends by a block 30, and again near their ends by a block 29 spaced from said block 30. The lower strap 28 of the arm 26 swings just clear of the bed plate, and welded to the arm immediately above the lower strap is a horizontal plate 31, which plate swings with the arm and has a width considerably greater than that of the arm, extending equally upon both sides thereof, and the plate 31, which constitutes a slewing table about a yard square, is provided with rollers 32 carried beneath it to run over the bed plate as the arm 26 swings. The table is extended by a plate 33 which is butt welded along its rear edge, that is to the edge nearest the pivot pin 25, and the pivot pin passes through a journal in the said plate 33. This plate projects laterally beyond the plate 31, towards the left hand side as viewed when looking in a direction along the arm 26 towards the former, and has near the extremity of its projecting part a boss 34. Secured to the swinging arm immediately above the upper strap 27 is a horizontal substantially triangular plate 35 through one corner of which is journalled the pivot pin 25, and which extends laterally from the left hand side of the arm to an apex where it has a boss 36 disposed vertically above the boss 34 of the table 31.

The cylinder 37 of a hydraulic piston and cylinder unit is carried horizontally in a cradle 38 constituted by a trussed girder framework secured to the floor and to the corner of the bed plate 12 nearest the superstructure 13 thereon, and the cylinder 37 has a piston rod 39 which extends towards and above the bed plate 12 and has its end pivotally connected to the table 31 and the triangular plate 35 by means of an eye 40 on the rod and a pin 41 passing through the eye and journalled in the bosses 34, 36. At the end opposite the piston rod the cylinder 37 is pivotally anchored at 43 to a post 42 cemented into the floor, and when the machine is in operation the piston and cylinder unit, by pulling upon the triangular plate 35 and the table 31 through the piston rod 39, cause the arm 26 to swing about its pivot and traverse the bed plate 12, the slight lateral movement which the traversing cylinder 37 has to make while performing this function being allowed for by its pivotal connection 43. Towards its outer end the swinging arm 26 carries a hydraulic piston and cylinder unit 44, horizontally mounted between and extending beyond the straps 27, 28 and the piston and cylinder unit has a piston rod 45 extending toward the pivot pin 25 and connected at its inner end to a cross head 46 mounted to slide along the arm between the straps 27, 28. The blocks 29, 30 have apertures to receive the piston-and-cylinder unit 44. The cross head has a nose 74 directed toward the pivot pin 25, and in a recess 73 in the nose is a roller 47 mounted centrally of the arm 26 and the cross head to rotate about a vertical axis on a spindle 70. Under the action of the hydraulic

cylinder 44 the roller 47 is caused to bear upon the back of a shoe 48 for shaping a work-piece upon the former 22 as will now be described.

The shoe 48 is a cast mild steel block about 3 ft. long, approximating in cross section to a square with a side of about 13 inches, and weighing about 12 cwt., and it rests horizontally upon the table 31 over which it is free to slide. Rollers may be provided beneath the block to facilitate sliding on the table, but it is found in practice that if the table surface is kept well lubricated rollers are not necessary as, despite its weight, the block will slide very readily on the table without them. The block has a horizontal recess 49 extending along its surface which faces toward the former 22, and three hardened steel inserts or liners 50 are fitted along the side and bottom faces of the recess to take up wear and are so shaped that when they are in position the vertical cross section of the recess, which is uniform along the whole length of the recess, is such as to correspond to the form of the outer or convex surface of the bumper which it is desired to produce upon the machine, as seen when the bumper is viewed in vertical cross section. The longitudinal centre line of the recess 49 is at the same height as that of the male former profile and the shoe with its longitudinally extending recess constitutes a female former movable with respect to the male former 22, with which it co-operates to shape a work-piece held in place between the former 22 and the shoe.

In addition to the main cylinder 44 for applying pressure to the back of the shoe 48 during the shaping of a work-piece, a further degree of control over the movements of the shoe is obtained by the provision of an auxiliary hydraulic shoe control cylinder 51 disposed upon the left hand of the main cylinder, as viewed in a direction looking toward the former. The auxiliary cylinder 51 is pivoted at one end to a frame 52 which is mounted to slide with the cross head 46 longitudinally of the arm 26 at the left hand side thereof, being secured at one end to the side of the cross head and at its other end to a block 53 sliding on guides 54 along the side of the arm. The cylinder 51 extends from its pivot point upon the frame 52 toward the shoe 48 and has a piston rod 55 which is pivotally connected to a built-up pivot block 56 sliding along a two-part slotted arm 57 which is integral with a saddle 58 mounted to slide along guide-slots 59 extending longitudinally of the back of the shoe 48. The saddle has upper and lower spaced horizontal limbs 71, extending along the back of the shoe 48, which are connected by a bridge-piece 72 at their left hand ends, where the slotted arm 57 joins them making an angle of somewhat less than a right angle with the limbs and the back of the shoe, and at their opposite ends 75 the limbs 71 of the saddle are pivotally connected to the nose of the cross head 46 by the spindle 70 which is journaled in them, and the roller 47 carried by the cross head bears upon the back of the shoe between the limbs of the saddle.

A bracket is secured at the edge of the machine bed-plate 12 upon the far side of the arm 26 from the shoe control cylinder 51, and the bracket has a horizontal flange 60 above the level of the slewing table 31 upon which flange is pivotally mounted a clamp cylinder 61 for clamping a work-piece to the former 22. The clamp cylinder has a piston rod 62 extending toward the former, which rod carries a pivotally mounted clamping jaw 63 on a level with the male former profile and

movable towards and away from the former and work-piece thereon, under the control of the clamp cylinder 61, the clamping edge being recessed so as to fit around the section of the work-piece near one end thereof and hold the work-piece firmly to the former 22 under the action of the pressure exerted by the clamp cylinder, at a position adjacent the end 23 of the former profile. The clamping jaw 63 (see Fig. 11) also has a horizontally projecting pin 76 centrally disposed within its recessed portion to pass through a hole in the work-piece for location in a hole in the former 22 so that the work-piece when clamped in position is positively held against slipping with respect to the former. The clamp cylinder 61 and its piston rod, are mounted at an angle to the former profile but the clamping jaw 63 is constrained to move substantially in a path normal to the horizontal centre line of the former profile at the position of clamping by means of a parallel linkage 64 pivoted upon the flange 60.

It is to be understood that, in the case of the specific machine illustrated and described herein, the work-pieces are not in general flat before they are put into the machine, having been pre-formed to a channel section which approximates to the section of, but is not fully reduced to the exact dimensions of the completed quarter bumper. The work-pieces when inserted are nearly straight, having only a slight lengthwise curvature, and the function of the machine described is to bend the work-piece to give it the considerable lengthwise curvature of the finished quarter-bumper while finishing the cross section of the bumper which has already been approximately formed. The preforming is carried out in another machine working on the same principle as that herein described which operates upon plain, straight, channel section work-pieces.

The operation of the machine herein described is as follows:

A preformed work-piece is dipped into a bath of drawing oil and allowed to drain, the oil serving to lubricate and cool the work-piece during the subsequent forming operation in the machine. The work-piece is then held against the fixed metal former 22 so that a portion of the work-piece near to that end which will eventually form the root end of the quarter bumper lies in contact with the corresponding end part 23, of slight lengthwise curvature, of the former profile, and the work-piece is clamped to the former at a point near to that end by the clamp jaw 63 which is moved towards the work-piece and former and held thereto under pressure by the clamp cylinder 61. The recess of the clamping jaw is shaped to conform to the outer surface of the preformed work-piece at the point of clamping. Since the work-piece is almost straight and the former profile is fairly sharply curved along its length, the two are only in contact for a short distance near the point of clamping, the remainder of the work-piece being free to move under pressure in relation to the former; the developed lengths of the former profile and the work-piece are substantially equal. It is to be noted that, for the sake of clarity, the work-piece has been omitted from all the figures of the drawings.

At the commencement of the forming operation the swinging arm 26 occupies the position shown in Figures 1 and 2, the traversing cylinder 37 being fully extended, so that the pressure cylinder 44, and the cross head 46 and roller 47, are in line with part of the work-piece and male

former lying close to the clamping jaw on the side further from the adjacent end 23 of the former. The shoe 48 is positioned so that the right hand end of it comes between the roller 47 and the former 22 with the work-piece thereon, and pressure is then applied by the cylinder 44, through the cross head 46 and roller 47, to the back of the shoe 48 so that the shoe is forced towards the former and driven tightly on to it around the work-piece over a limited area in front of the roller 47.

The table 31 and the arm 26 carrying the pressure cylinder 44, cross head 46, and roller 47 are then caused to swing slowly about the pivot pin 25 in a direction away from the clamping jaw by means of the traverse cylinder 37, but the table does not carry the shoe 48 with it. Instead, the shoe slides on the table 31, and the roller 47 on the cross-head 46 begins to travel along the back of the shoe 48, and the consequential transfer of the position of application of the pressure on the back of the shoe towards the other end thereof causes the shoe to roll slowly along the work-piece and around the lengthwise curve of the male former, swinging angularly as it does so, but independently of the arm 26, so that the pressure of the shoe 48 upon the work-piece is transferred gradually and progressively along the work-piece towards what will be the toe end of the finished quarter bumper, and the metal is progressively bent round and shaped on to the male former 22. Owing to the fact that this shaping on to the former is accompanied by compression to bring the metal to take the curve of the former as viewed in plan, the quarter-bumper is formed without producing any undesirable crinkles or distortion, and this result would be obtained even if the flange of the bumper above or below the male former, or both above and below were quite a deep one, and the radius of the bumper were quite sharp. The metal thickens up slightly on the inside of the curve, but is not overstrained in any way.

It will be clear that when shaping the work-piece to the more sharply curved parts of the former profile, the shoe 48 must swing round more rapidly than when it is shaping the less curved parts, and it is not always possible to produce the requisite motion of the shoe by means of the pressure cylinder 44 alone, particularly where the former 22 is sharply curved. The auxiliary or shoe control cylinder 51 is therefore provided in order, where necessary, to assist the shoe 48 to swing. The mounting of the cylinder 51 is such that it moves towards or away from the pivot pin 25 with the cross head 46, and its connection to the back of the shoe 48 by means of the saddle 58 and slotted arm 57 carried thereby, enables it, firstly, to press upon the back of the shoe 48 at an angle thereto and in fixed relation to the cross head 46 and roller 47 without preventing the sliding of the shoe upon the table 31 independently of the arm 26, and secondly, to be brought into action to press upon the shoe 48 only when required. The block 56 sliding in the slot of the arm 57 constitutes a lost motion connection between the piston rod 55 and the arm so that the shoe control cylinder 51 can only have an influence upon the shoe 48 when the lost motion has been first taken up, and this only happens if the shoe lags in its swinging motion around the former 22; when this occurs the cylinder 51 backs up the shoe 48, through the saddle 58, at a position displaced horizontally from the

roller 47 and in advance thereof, that is between the roller and the end of the shoe toward which the roller is travelling, and so produces the necessary couple to swing the shoe 48 at increased speed. Figures 3 and 4 of the drawings show the movable parts of the machine in the relative positions which they occupy at two different stages in the cycle of operations; Figure 3 shows the relative positions when the work-piece is not quite half formed, and Figure 4, the positions when the forming is almost complete.

When the forming of the quarter-bumper has been completed, the pressure upon the back of the shoe is released and the traversing cylinder 37 is reversed to pull the shoe off the work; the finished bumper work-piece can then be removed by withdrawing the clamping jaw, and a further work-piece inserted. The shoe control cylinder 51 is used to assist in pulling the shoe off the work and also in restoring the shoe to the position (shown in Figure 1) where it is square to the line of pressure of the pressure cylinder 44 for the commencement of the next working cycle, the arm 26 being returned to its initial position (Figure 1) by the traversing cylinder 37.

The pressure employed in forming the work-piece is of the order of 2,000 lbs. per square inch, and the hydraulic pressure is conveyed to the various cylinders of the machine by reinforced flexible pipes, not shown in the drawings. A constant-delivery type pump is automatically controlled to maintain the working pressure in the various hydraulic circuits. The time taken to form a quarter-bumper in the machine described is about a minute. An adjustable relief valve is provided in the pressure line to the swinging pressure cylinder 44 in order to prevent excessive fluid pressure in said cylinder during forming of the work-piece.

It will be understood that when the shoe 48 is pressing a work-piece to a part of the former 22 where the distance of the former profile from the pivot of the arm 26 is increasing, there will be increased resistance to the progress of the swinging arm as compared with when the distance of the former profile from the pivot 25 is constant, whereas when said distance is decreasing the resistance to swinging is decreased; these conditions under which the resistance to swinging is increased or decreased may be regarded as analogous to "uphill" or "downhill" movement of the shoe respectively. The constant delivery pump and the relief valve aforementioned keep the pressure exerted by the cylinder 44 substantially constant whether the movement of the shoe is "uphill" or "downhill," that is whether the piston rod 45 is moving into or out of the pressure cylinder, but "downhill" movement of the shoe results in a tendency of the arm 26 to swing more rapidly, and it is important that the movement of the arm and shoe should be sufficiently slow to allow the metal of the work-piece time to flow as it is shaped. Therefore, a control valve 65 is provided to throttle the outflow of fluid from the exhaust side of the traverse cylinder 37 so as to keep the speed of the arm 26 below a predetermined maximum and prevent unduly rapid folding action upon the work-piece occurring at any point in the cycle.

The valve 65 is carried upon the head-plate 15 and has a cam follower to engage the profile of a cam 66 mounted to rotate with the pivot pin 25, and the cam profile is so related in shape

to the male former profile as to cause the valve 65 to throttle the traverse cylinder 37 and reduce its pull upon the arm 26 when the shoe is moving "downhill" around the former 22. The valve 65 and cam 66 also serve to cause the traverse cylinder to slow up and stop the movement of the swinging arm as it reaches the end of its travel, and so prevent the arm from running off the bed plate 12, and the shoe from sliding off the table 34. A second control valve 67 mounted on a bracket upon the head plate 15, has a cam follower to engage a further cam surface upon the side of the cam 66, and the valve 67 serves to influence the operation of the shoe control cylinder 51 in accordance with the varying profile of the male former 22 as the arm 26 swings.

Instead of making a bumper from a preformed flanged work-piece it may be made from a flat metal bar in one operation, the shoe, as it rolls around the former, folding over the edges of the work-piece to form the flanges in addition to bending and shaping it. The hydraulically operated clamping jaw can in this case, if desired, be utilised for shaping the short length of the work-piece which it engages.

We claim:

1. In a metal working machine the combination of a machine frame, a curved former on said frame, a flat table mounted on the frame below the former, means to hold a work-piece in place against the former for shaping, a shoe able to roll on the work-piece against the former in a horizontal plane of movement which shoe rests on the table and is capable of being moved over the table linearly and angularly in any direction in the horizontal plane, fluid-pressure-operated means to press the shoe, work-piece and former together, said fluid-pressure-operated means being provided with a nose to apply the pressure to the back of the shoe and being so mounted on the machine frame that the nose is capable of moving laterally for shifting the place of contact between nose and shoe along the shoe, and means to effect said lateral movement of the nose to shift the place of application of pressure to the work-piece progressively along its surface while the fluid pressure is maintained.

2. In a metal working machine the combination of a machine frame, a curved former on said frame, a flat table mounted on the frame below the former, means to hold a work-piece in place against the former for shaping, a heavy shoe able to roll on the work-piece against the former in a horizontal plane of movement which shoe rests on the table and has a broad flat bottom so that it is in stable equilibrium thereon and is capable of being pushed and pulled over the table linearly and angularly in any direction in the horizontal plane, fluid-pressure-operated means to press the shoe, work-piece and former together, and which is provided with a nose to apply the pressure to the back of the shoe which nose is shaped to make substantially line-contact with the shoe along a substantially vertical line, said fluid-pressure-operated means being so mounted on the machine frame that the nose is capable of moving laterally for shifting the line of contact between nose and shoe along the shoe, and means to effect said lateral movement of the nose to shift the place of application of pressure to the work-piece progressively along its surface while the fluid pressure is maintained, the shoe being sufficiently heavy

5 to keep the metal of the work-piece flowing smoothly by reason of the inertia of the shoe as it rolls thereon thereby substantially obviating distortion and the formation of undesirable crinkles in the work-piece.

3. In a metal working machine the combination of a machine frame, a former on said frame which is convexly curved in the horizontal direction, a flat table mounted on the frame below the former, means to hold a work-piece in place against the forming for shaping, a heavy shoe, straight in the horizontal direction, and able to roll on the work-piece against the former in a horizontal plane of movement which shoe rests on the table and has a broad flat bottom so that it is in stable equilibrium thereon and is capable of being pushed and pulled over the table linearly and angularly in any direction in the horizontal plane, fluid-pressure-operated means to press the shoe, work-piece and former together, and which is provided with a nose to apply the pressure to the back of the shoe which nose is shaped to make substantially line-contact with the shoe along a substantially vertical line, said fluid-pressure-operated means being so mounted on the machine frame that the nose is capable of moving laterally for shifting the line of contact between the nose and shoe along the shoe, and means to effect said lateral movement of the nose to shift the place of application of pressure to the work-piece progressively along its surface while the fluid pressure is maintained, the shoe being sufficiently heavy to keep the metal of the work-piece flowing smoothly by reason of the inertia of the shoe as it rolls thereon thereby substantially obviating distortion and the formation of undesirable crinkles in the work-piece.

4. In a metal working machine the combination of a machine frame, a male former on said frame which is convexly curved in the horizontal direction, a flat table mounted on the frame below the former, means to hold a work-piece in place against the former for shaping, a heavy shoe constituting a female former and straight in the horizontal direction, and able to roll on the work-piece against the male former in a horizontal plane of movement which shoe rests on the table and has a broad flat bottom so that it is in stable equilibrium thereon and is capable of being pushed and pulled over the table linearly and angularly in any direction in the horizontal plane, fluid-pressure-operated means to press the shoe, work-piece and male former together, and which is provided with a nose to apply the pressure to the back of the shoe which nose is shaped to make substantially line-contact with the shoe along a substantially vertical line, said fluid-pressure-operated means being so mounted on the machine frame that the nose is capable of moving laterally for shifting the line of contact between nose and shoe along the shoe, and means to effect said lateral movement of the nose to shift the place of application of pressure to the work-piece progressively along its surface while the fluid pressure is maintained, the shoe being sufficiently heavy to keep the metal of the work-piece flowing smoothly by reason of the inertia of the shoe as it rolls thereon thereby substantially obviating distortion and the formation of undesirable crinkles in the work-piece.

5. In a metal working machine the combination of a machine frame, a curved former on said frame, a flat table mounted on the frame below the former, means to hold a work-piece in place against the former for shaping a shoe able to roll

11

on the work-piece against the former in a horizontal plane of movement which shoe rests on the table and is capable of being moved over the table linearly and angularly in any direction in the horizontal plane, an arm mounted on the frame to swing about a vertical axis with its pivot on the opposite side of the former to the work-piece and shoe which arm extends across the former, work-piece and shoe and beyond the back of the shoe, fluid-pressure-operated means mounted upon the swinging arm behind the shoe to press the shoe, former and work-piece together, said fluid-pressure-operated means being provided with a nose to apply the pressure to the back of the shoe which nose moves laterally as the arm swings thereby shifting the place of contact between nose and shoe along the shoe, and means to swing the arm and effect said lateral movement of the nose to shift the place of application of pressure to the work-piece progressively along its surface while the fluid pressure is maintained.

6. In a metal working machine the combination of a machine frame, a curved former on said frame, means to hold a work-piece in place against the former for shaping, an arm mounted on the frame to swing about a vertical axis with its pivot on the opposite side of the former to the work-piece which arm extends from its pivot across and beyond the former and work-piece, a flat table on the arm below the former, a shoe able to roll on the work-piece against the former in a horizontal plane of movement which shoe rests on the table and is capable of being moved over the table linearly and angularly in any direction in the horizontal plane, fluid-pressure-operated means mounted upon the swinging arm behind the shoe to press the shoe, former and work-piece together, said fluid-pressure-operated means being provided with a nose to apply the pressure to the back of the shoe which nose moves laterally as the arm swings thereby shifting the place of contact between nose and shoe along the shoe, and means to swing the arm and effect said lateral movement of the nose to shift the place of application of pressure to the work-piece progressively along its surface while the fluid pressure is maintained.

7. In a metal working machine the combination of a machine frame, a curved former on said frame, means to hold a work-piece in place against the former for shaping, an arm mounted on the frame to swing about a vertical axis with its pivot on the opposite side of the former to the work-piece which arm extends from its pivot across and beyond the former and work-piece, a flat table on the arm below the former, a heavy shoe able to roll on the work-piece against the former in a horizontal plane of movement which shoe rests on the table and has a broad flat bottom so that it is in stable equilibrium thereon and is capable of being pushed and pulled over the table linearly and angularly in any direction in the horizontal plane, a hydraulic piston-and-cylinder unit mounted upon the arm behind the shoe to press the shoe, former and work-piece together, said fluid-pressure-operated means being provided with a nose to apply the pressure to the back of the shoe which nose is shaped to make substantially line contact with the shoe along a substantially vertical line, the nose moving laterally as the arm swings thereby shifting the line of contact between nose and shoe along the shoe, and means to swing the arm and effect said lateral movement of the nose to shift the place of application of pressure to the work-piece progressively along its surface while the fluid pressure is

75 maintained, the shoe being sufficiently heavy to keep the metal of the work-piece flowing smoothly by reason of the inertia of the shoe as it rolls thereon thereby substantially obviating distortion and the formation of undesirable crinkles in the work-piece.

8. In a metal working machine the combination of a machine frame, a curved former on said frame, means to hold a work-piece in place against the former for shaping, an arm mounted on the frame to swing about a vertical axis with its pivot on the opposite side of the former to the work-piece which arm extends from its pivot across and beyond the former and work-piece, a flat table on the arm below the former, a shoe able to roll on the work-piece against the former in a horizontal plane of movement which shoe rests on the table and is capable of being moved over the table linearly and angularly in any direction in the horizontal plane, a hydraulic piston-and-cylinder unit mounted upon the swing arm behind the shoe to press the shoe, former and work-piece together, a piston-rod extending from said unit toward the back of the shoe, a crosshead secured at the end of the piston-rod to slide to and fro along the arm, guideways on the arm for the crosshead, a roller mounted on the crosshead with its axis vertical to apply the pressure to the back of the shoe, the place of contact between roller and shoe shifting along the back of the shoe as the arm swings, and means to swing the arm to effect such shifting of said place of contact and thereby shift the place of application of pressure to the work-piece progressively along its surface while the hydraulic pressure is maintained.

9. In a metal working machine the combination of a machine frame, a curved former on said frame, means to hold a work-piece in place against the former for shaping, an arm mounted on the frame to swing about a vertical axis with its pivot on the opposite side of the former to the work-piece which arm extends from its pivot across and beyond the former and work-piece, a flat table on the arm below the former, a heavy shoe able to roll on the work-piece against the former in a horizontal plane of movement which shoe rests on the table and has a broad flat bottom so that it is in stable equilibrium thereon and is capable of being pushed and pulled over the table linearly and angularly in any direction in the horizontal plane, a hydraulic piston-and-cylinder unit mounted upon the arm behind the shoe to press the shoe, former and work-piece together, a piston-rod extending from said unit toward the back of the shoe, a crosshead secured at the end of the piston-rod to slide to and fro along the arm, guideways on the arm for the crosshead, a roller mounted on the crosshead with its axis vertical to apply the pressure to the back of the shoe, the place of contact between roller and shoe shifting along the back of the shoe as the arm swings, and fluid-pressure-operated means to swing the arm to effect such shifting of said place of contact and thereby shifting the place of application of pressure to the work-piece progressively along its surface while the hydraulic pressure is maintained, the shoe being sufficiently heavy to keep the metal of the work-piece flowing smoothly by reason of the inertia of the shoe as it rolls thereon thereby substantially obviating distortion and the formation of undesirable crinkles in the work-piece.

10. In a metal working machine the combination of a machine frame, a curved former on said frame, a flat table mounted on the frame below the former, means to hold a work-piece in place against the former for shaping, a shoe able to roll on the work-piece against the former in a horizontal plane of movement which shoe rests on the table and is capable of being moved over the table linearly and angularly in any direction in the horizontal plane, main fluid-pressure-operated means to press the shoe, work-piece and former together, said main fluid-pressure-operated means being provided with a nose to apply the pressure to the back of the shoe and being so mounted on the machine frame that the nose is capable of moving laterally for shifting the place of contact between nose and shoe along the shoe, means to effect said lateral movement of the nose to shift the place of application of pressure to the work-piece progressively along its surface while the fluid pressure is maintained, and auxiliary fluid-pressure-operated means mounted on the frame and operatively connected to the shoe at a place of connection normally spaced apart along the shoe from the place of contact between nose and shoe whereby added control of the angular movements of the shoe is provided for.

11. In a metal working machine the combination of a machine frame, a curved former on said frame, a flat table mounted on the frame below the former, means to hold a work-piece in place against the former for shaping, a heavy shoe able to roll on the work-piece against the former in a horizontal plane of movement which shoe rests on the table and has a broad flat bottom so that it is in stable equilibrium thereon and is capable of being pushed and pulled over the table linearly and angularly in any direction in the horizontal plane, main fluid-pressure-operated means to press the shoe, work-piece and former together and which is provided with a nose to apply the pressure to the back of the shoe which nose is shaped to make substantially line contact with the shoe along a substantially vertical line, said main fluid-pressure-operated means being so mounted on the machine frame that the nose is capable of moving laterally for shifting the line of contact between nose and shoe along the shoe, means to effect said lateral movement of the nose to shift the place of application of pressure to the work-piece progressively along its surface while the fluid pressure is maintained, the shoe being sufficiently heavy to keep the metal of the work-piece flowing smoothly by reason of the inertia of the shoe as it rolls thereon thereby substantially obviating distortion and the formation of undesirable crinkles in the work-piece, and auxiliary fluid-pressure-operated means mounted on the frame and operatively connected to the shoe at a place of connection spaced apart along the shoe from the line of contact between nose and shoe, with means serving to keep said place of connection and said line of contact apart during shifting of the line of contact along the shoe, whereby added control of the angular movements of the shoe is provided for.

12. In a metal working machine the combination of a machine frame, a curved former on said frame, a flat table mounted on the frame below the former, means to hold a work-piece in place against the former for shaping, a shoe able to roll on the work-piece against the former in a horizontal plane of movement which shoe rests

on the table and is capable of being moved over the table linearly and angularly in any direction in the horizontal plane, main fluid-pressure-operated means to press the shoe, work-piece and former together, said main fluid-pressure-operated means being provided with a nose to apply the pressure to the back of the shoe and being so mounted on the machine frame that the nose is capable of moving laterally for shifting the place of contact between nose and shoe along the shoe, means to effect said lateral movement of the nose to shift the place of application of pressure to the work-piece progressively along its surface while the fluid pressure is maintained a saddle mounted to slide to and fro along the shoe, guideways on the shoe for the saddle, connecting means between the saddle and the nose such that they travel together along the shoe, and auxiliary fluid-pressure-operated means mounted on the frame and connected to the saddle at a place of connection spaced along the shoe from the nose whereby added control of the angular movements of the shoe is provided for.

13. In a metal working machine the combination of a machine frame, a curved former on said frame, a flat table mounted on the frame below the former, means to hold a work-piece in place against the former for shaping, a heavy shoe able to roll on the work-piece against the former in a horizontal plane of movement which shoe rests on the table and has a broad flat bottom so that it is in stable equilibrium thereon and is capable of being pushed and pulled over the table linearly and angularly in any direction in the horizontal plane, main fluid-pressure-operated means to press the shoe, work-piece and former together and which is provided with a nose to apply the pressure to the back of the shoe which nose is shaped to make substantially line contact with the shoe along a substantially vertical line, said main fluid-pressure-operated means being so mounted on the machine frame that the nose is capable of moving laterally for shifting the line of contact between nose and shoe along the shoe, means to effect said lateral movement of the nose to shift the place of application of pressure to the work-piece progressively along its surface while the fluid pressure is maintained, the shoe being sufficiently heavy to keep the metal of the work-piece flowing smoothly by reason of the inertia of the shoe as it rolls thereon thereby substantially obviating distortion and the formation of undesirable crinkles in the work-piece, a saddle mounted to slide to and fro along the shoe, guideways on the shoe for the saddle, connecting means between the saddle and the nose such that they travel together along the shoe, and auxiliary fluid-pressure-operated means mounted on the frame and connected to the saddle at a place of connection spaced along the shoe from the nose whereby added control of the angular movements of the shoe is provided for.

14. In a metal working machine the combination of a machine frame, a curved former on said frame, means to hold a work-piece in place against the former for shaping, an arm mounted on the frame to swing about a vertical axis with its pivot on the opposite side of the former to the work-piece which arm extends from its pivot across and beyond the former and work-piece, a flat table on the arm below the former, a shoe able to roll on the work-piece against the former in a horizontal plane of movement which shoe rests on the table and is capable of being moved over the table linearly and angularly in any direction in

the horizontal plane, main fluid-pressure-operated means mounted upon the swinging arm behind the shoe to press the shoe, former and work-piece together said main fluid-pressure-operated means being provided with a nose to apply the pressure to the back of the shoe which nose moves laterally as the arm swings thereby shifting the place of contact between nose and shoe along the shoe, and means to swing the arm and effect said lateral movement of the nose to shift the place of application of pressure to the work-piece progressively along its surface while the fluid pressure is maintained, a saddle mounted to slide along the shoe, guideways on the shoe for the saddle, connecting means between the saddle and the nose such that they travel together along the shoe, and auxiliary fluid-pressure-operated means also mounted on the arm behind the shoe and connected to the saddle by a lost-motion connection at a place spaced along the shoe from the nose whereby added control of the angular movements of the shoe is provided for.

15. In a metal working machine the combination of a machine frame, a curved former on said frame, means to hold a work-piece in place against the former for shaping, an arm mounted on the frame to swing about a vertical axis with its pivot on the opposite side of the former to the work-piece which arm extends from its pivot across and beyond the former and work-piece, a flat table on the arm below the former, a heavy shoe able to roll on the work-piece against the former in a horizontal plane of movement which shoe rests on the table and has a broad flat bottom so that it is in stable equilibrium thereon and is capable of being pushed and pulled over the table linearly and angularly in any direction in the horizontal plane, a main hydraulic piston-and-cylinder unit mounted upon the swinging arm behind the shoe to press the shoe, former and work-piece together said main piston-and-cylinder unit being provided with a nose to apply the pressure to the back of the shoe which nose is shaped to make substantially line contact with the shoe along a substantially vertical line, the nose moving laterally as the arm swings thereby shifting the line of contact between nose and shoe along the shoe, and means to swing the arm and effect said lateral movement of the nose to shift the place of application of pressure to the work-piece progressively along its surface while the fluid pressure is maintained, the shoe being sufficiently heavy to keep the metal of the work-piece flowing smoothly by reason of the inertia of the shoe as it rolls thereon thereby substantially obviating distortion and the formation of undesirable wrinkles in the work-piece, a saddle mounted to slide along the shoe, guideways on the shoe for the saddle, connecting means between the saddle and the nose such that they travel together along the shoe, and an auxiliary hydraulic piston-and-cylinder unit having its cylinder pivotally mounted upon the arm behind the shoe and its piston operatively connected by a lost-motion connection to the saddle at a place spaced along the shoe from the nose whereby added control of the angular movements of the shoe is provided for.

16. In a metal working machine the combination of a machine frame, a curved former on said frame, means to hold a work-piece in place against the former for shaping, an arm mounted on the frame to swing about a vertical axis with its pivot on the opposite side of the former to the work-piece which arm extends from its pivot across and beyond the former and work-piece,

5 a flat table on the arm below the former, a shoe able to roll on the work-piece against the former in a horizontal plane of movement which shoe rests on the table and is capable of being moved over the table linearly and angularly in any direction in the horizontal plane, a main hydraulic piston-and-cylinder unit mounted upon the swinging arm behind the shoe to press the shoe, former and work-piece together, a main piston-rod extending from said unit toward the back of the shoe, a crosshead secured at the end of the piston-rod to slide to and fro along the arm, guideways on the arm for the crosshead, a roller mounted on the crosshead with its axis vertical to apply the pressure to the back of the shoe the place of contact between roller and shoe shifting along the shoe as the arm swings, means to swing the arm to effect such shifting of said place of contact and thereby shift the place of application of pressure to the work-piece progressively along its surface while the hydraulic pressure is maintained, a saddle mounted to slide along the shoe, guideways on the shoe for the saddle, connecting means between the saddle and the roller such that they travel together along the shoe, an auxiliary hydraulic piston-and-cylinder unit having its cylinder mounted to slide with the crosshead along the arm, an auxiliary piston-rod extending from said auxiliary piston-and-cylinder unit toward the back of the shoe and connected to the saddle by means of a lost motion connection at a place spaced along the shoe from the roller whereby added control of the angular movements of the shoe is provided for.

17. In a metal working machine the combination of a machine frame, a curved former on said frame, means to hold a work-piece in place against the former for shaping, an arm mounted on the frame to swing about a vertical axis with its pivot on the opposite side of the former to the work-piece which arm extends from its pivot across and beyond the former and work-piece, a flat table on the arm below the former, a shoe able to roll on the work-piece against the former in a horizontal plane of movement which shoe rests on the table and is capable of being moved over the table linearly and angularly in any direction in the horizontal plane, a main hydraulic piston-and-cylinder unit mounted upon the swinging arm behind the shoe to press the shoe, former and work-piece together, a main piston-rod extending from said unit toward the back of the shoe, a crosshead secured at the end of the piston-rod to slide to and fro along the arm, guideways on the arm for the crosshead, a roller mounted upon a vertical spindle on the crosshead to apply the pressure to the back of the shoe the place of contact between roller and shoe shifting along the shoe as the arm swings, means to swing the arm to effect such shifting of said place of contact and thereby shift the place of application of pressure to the work-piece progressively along its surface while the hydraulic pressure is maintained, a saddle mounted to slide along the shoe and guideways on the shoe for the saddle, the spindle for the roller on the crosshead being journaled in said saddle so that the saddle is thereby pivotally connected to the roller to travel with it along the shoe, a frame carried on the side of the arm and capable of sliding along it with the crosshead, one end of said frame being secured to the crosshead and the other end being mounted on guideways on the arm, an auxiliary hydraulic piston-

and-cylinder unit having its cylinder pivotally mounted on the frame, an auxiliary piston-rod extending from said auxiliary piston-and-cylinder unit toward the back of the shoe and connected to the saddle by means of a lost motion connection at a place spaced along the shoe from the roller whereby added control of the angular movements of the shoe is provided for.

18. In a metal working machine the combination of a machine frame, a curved former on said frame, means to hold a work-piece in place against the former for shaping, an arm mounted on the frame to swing about a vertical axis with its pivot on the opposite side of the former to the work-piece which arm extends from its pivot across and beyond the former and work-piece, a flat table on the arm below the former, a shoe able to roll on the work-piece against the former in a horizontal plane of movement which shoe rests on the table and is capable of being moved over the table linearly and angularly in any direction in the horizontal plane, a main hydraulic piston-and-cylinder unit mounted upon the swinging arm behind the shoe to press the shoe, former and work-piece together, a main piston-rod extending from said unit toward the back of the shoe, a crosshead secured at the end of the piston-rod to slide to and fro along the arm, guideways on the arm for the crosshead, a roller mounted upon a vertical spindle on the crosshead to apply the pressure to the back of the shoe the place of contact between roller and shoe shifting along the shoe as the arm swings, means to swing the arm to effect such shifting of said place of contact and thereby shift the place of application of pressure to the work-piece progressively along its surface while the hydraulic pressure is maintained, a saddle mounted to slide along the shoe and guideways on the shoe for the saddle, the spindle for the roller on the crosshead being journaled in said saddle so that the saddle is thereby pivotally connected to the roller to travel with it along the shoe, a substantially horizontal longitudinally-slotted arm upon the saddle extending rearwardly from a position at the back of, and spaced along, the shoe from the roller, a pivot block adapted to slide along the slot in said slotted arm, a frame carried on the side of the swinging arm and capable of sliding along it with the crosshead, one end of said frame being secured to the crosshead and the other end being mounted on guideways on the swinging arm, an auxiliary hydraulic piston-and-cylinder unit having its cylinder pivotally mounted on the frame, and an auxiliary piston-rod extending from said auxiliary piston-and-cylinder unit toward the back of the shoe and pivotally connected to the pivot block on the pivot block on the saddle arm whereby added control of the angular movements of the shoe is provided for.

19. In a metal working machine the combination of a machine frame, a curved former on said frame, fluid-operated clamping means to hold a work-piece in place against the former for shaping, an arm mounted on the frame to swing about a vertical axis with its pivot on the opposite side of the former to the work-piece which arm extends from its pivot across and beyond the former

and work-piece, a flat table on the arm below the former, a heavy shoe able to roll on the work-piece against the former in a horizontal plane of movement which shoe rests on the table and has a broad flat bottom so that it is in stable equilibrium thereon and is capable of being pushed and pulled over the table linearly and angularly in any direction in the horizontal plane, a main piston-and-cylinder unit mounted upon the swinging arm behind the shoe to press the shoe, former and work-piece together, a main piston-rod extending from said unit toward the back of the shoe, a crosshead secured at the end of the piston-rod to slide to and fro along the arm, guideways on the arm for the crosshead, a roller mounted upon a vertical spindle on the crosshead to apply the pressure to the back of the shoe the place of contact between roller and shoe shifting along the shoe as the arm swings, fluid-pressure-operated means to swing the arm to effect such shifting of said place of contact and thereby shift the place of application of pressure to the work-piece progressively along its surface while the hydraulic pressure is maintained, the shoe being sufficiently heavy to keep the metal of the work-piece flowing smoothly by reason of the inertia of the shoe as it rolls thereon thereby substantially obviating distortion and the formation of undesirable crinkles in the work-piece, a saddle mounted to slide along the shoe and guideways on the shoe for the saddle, the spindle for the roller on the crosshead being journaled in said saddle so that the saddle is thereby pivotally connected to the roller to travel with it along the shoe, a substantially horizontal longitudinally-slotted arm upon the saddle extending rearwardly from a position at the back of, and spaced along, the shoe from the roller, a pivot block adapted to slide along the slot in said slotted arm, a frame carried on the side of the swinging arm and capable of sliding along it with the crosshead, one end of said frame being secured to the crosshead and the other end being mounted on guideways on the swinging arm, an auxiliary hydraulic piston-and-cylinder unit having its cylinder pivotally mounted on the frame, and an auxiliary piston-rod extending from said auxiliary piston-and-cylinder unit toward the back of the shoe and pivotally connected to the pivot block on the saddle arm whereby added control of the angular movements of the shoe is provided for.

ALBERT MAURICE REDMAN.
ARTHUR FREDERICK FROST.
